H. BLOOMER.
LOADING APPARATUS.
APPLICATION FILED AUG. 4, 1917.

Patented Nov. 20, 1917.

2 SHEETS—SHEET 2.

UNITED STATES PATENT OFFICE.

HENRY BLOOMER, OF HULL, WISCONSIN.

LOADING APPARATUS.

1,246,856.

Specification of Letters Patent. Patented Nov. 20, 1917.

Application filed August 4, 1917. Serial No. 184,526.

To all whom it may concern:

Be it known that I, HENRY BLOOMER, a citizen of the United States, residing at Hull, in the county of Marathon and State 5 of Wisconsin, have invented certain new and useful Improvements in Loading Apparatus, of which the following is a specification, reference being had to the accompanying drawings.

10 This invention relates to certain improvements in loading apparatus and has relation more particularly to a device of this general character especially designed and adapted for use in connection with hay or 15 the like and it is an object of the invention to provide an apparatus of this general character adapted to be employed in connection with a hay rack or the like and which serves to deposit the hay to the forward 20 end portion of the rack and which includes a conveyer movable to the forward portion of the rack in order to facilitate loading at the rear portion of the rack.

The invention also has for an object to 25 provide a novel and improved apparatus of this general character including a conveyer positioned adjacent the upper portion of the hay rack or the like and movable longitudinally thereof together with means for 30 imparting movement to the conveyer in opposite directions.

Furthermore it is an object of the invention to provide a novel and improved device of this general character wherein the conveyer includes an endless apron and wherein 35 said apron is operatively engaged with a driving means when the conveyer is at the limit of its movement in one direction.

The invention consists in the details of 40 construction and in the combination and arrangement of the several parts of my improved loading apparatus wherein certain important advantages are attained and the device rendered simpler, less expensive and 45 otherwise more convenient and advantageous for use, as will be hereinafter more fully set forth.

The novel features of my invention will hereinafter be definitely claimed.

50 In order that my invention may be the better understood I will now proceed to describe the same with reference to the accompanying drawings wherein,

Figure 1 is a view in side elevation illustrating an apparatus constructed in accord-

ance with an embodiment of my invention and applied to a hay rack;

Fig. 2 is a view in top plan of the construction as illustrated in Fig. 1;

Fig. 3 is a sectional view taken substantially on the line 3-3 of Fig. 2;

Fig. 4 is a fragmentary view in side elevation of the upper rear portion of the device as herein embodied, and opposite to the disclosure in Fig. 1; and

Fig. 5 is a fragmentary sectional view taken substantially on the line 5-5 of Fig. 1.

As disclosed in the accompanying drawings H denotes a hay rack having disposed longitudinally thereof and extending outwardly from a side a footboard B to afford means whereby an operator may have convenient access to the upper portion of the rack. Each side of the rack H at its top is provided with a horizontal trackway T afforded by the vertically spaced parallel beams 1 and slidably engaged within each of the trackways T is a pair of longitudinally spaced bearings 2 connected by a side board 3. Rotatably supported by each pair of transversely alined bearings 2 is a shaft 4 having suitably fixed thereto the drums 5. Disposed around the drums 5 is an endless conveyer 6. In practice it is preferred that the side boards 3 be of a length not over and preferably less than one half the length of the rack H so that when the conveyer 6 is positioned adjacent the rear portion of the rack H the hay or the like deposited upon the conveyer may be delivered to the forward end portion of the rack H.

The rear shaft 4 has suitably affixed to an extended portion thereof a gear wheel 7 in mesh with an idle gear 8 rotatably supported by an adjacent beam 1 and the gear 8 is in mesh with a gear 9 carried by an extended portion of a shaft 10 extending transversely of and rotatably supported by the rear portion of the rack H. The shaft 10 has also fixed thereto a sprocket wheel 11 around which is disposed the sprocket chain 12 operatively engaged with a sprocket wheel 14 suitably fixed to a rear supporting wheel W. The gears 7, 8 and 9 together with the sprocket 11 are positioned at the same side of the rack H as the footboard B and in order that the footboard B may afford no obstruction to the requisite travel of the chain 12 I provide said board B with

the suitable opening 15 through which the chain 12 passes.

Fixed to the shaft 10 intermediate the sides of the rack H is a drum 16 around 5 which passes an endless apron 17 which is also disposed around the drum 18 fixed to the shaft 19 rotatably supported by the upper beams 1 at a predetermined point in advance of the shaft 10 so that the apron 10 17 is arranged on a predetermined upward incline and serves as an elevator to properly discharge the hay or the like upon the upper stretch of the conveyer 6 when said conveyer is operatively engaged with the 15 idle gear 8. In practice any preferred type of hay loader is adapted to be hitched to the rear portion of the rack H and adjusted to deliver upon the elevating apron 17 as the hay loader *per se* forms no part of my 20 present invention, a description and illustration thereof is believed to be unnecessary.

The forward end portion of each of the side boards 3 is provided with an outstanding extension 20 having secured thereto, at 25 21 a flexible member 22 which extends forwardly of the rack H and is operatively engaged with a drum 23 fixed to the transverse shaft 24 rotatably supported by the forward end portion of the rack H and 30 preferably the upper beams 1. The end portion of the shaft 24 adjacent the board B is provided exteriorly of the rack with an operating crank 25. Also secured to the extended portion of the shaft 24 and adjacent 35 the crank 25 is a ratchet 26 with which co-acts a pawl 27 for holding the shaft 24 against retrograde movement. When it is desired to position the conveyer 6 at the forward end portion of the rack H in order 40 to facilitate the loading of the rear portion of the rack it is only necessary to impart requisite rotation to the crank 25.

Depending from the rear end portion of each of the side boards 3 is an extension 28 having operatively engaged therewith as at 45 29 the flexible member 30 disposed from an idle pulley 31 rotatably supported by the rear portion of the rack H and engaged with a drum 32 fixed to the transverse shaft 33 50 rotatably supported by the rear portion of the rack H at a predetermined point below the pulley 31. The end portion of the shaft 33 remote from the side of the rack provided 55 with a footboard B extends exteriorly of the rack and is provided with an operating crank 34. The extended portion of the shaft 33 has also fixed thereto the ratchet 35 with which co-acts the pawl 36 to hold said shaft 33 against retrograde 60 movement. When it is desired to return the conveyer 6 to the rear end portion of the rack H the pawl 27 is disengaged from the ratchet 26 and desired rotation imparted to the shaft 33 under the influence of the crank 34. When the conveyer 6 reaches the limit 65

of its inward movement the gear 7 is brought into mesh with the gear 8 so that upon the travel of the hay rack H the upper stretch of the conveyer 6 will be caused to move forwardly.

From the foregoing description, it is thought to be obvious that a loading apparatus constructed in accordance with my invention is particularly well adapted for use by reason of the convenience and facility with which it may be assembled and operated and it will also be obvious that my invention is susceptible of some change and modification without materially departing from the principle and spirit thereof and for this reason I do not wish to be understood as limiting myself to the precise arrangement and formation of the several parts herein shown in carrying out my invention in practice except as hereinafter claimed.

I claim:

1. In combination with a container provided with parallel trackways at the upper portions of the sides thereof, side boards slidably engaged with said trackways, shafts rotatably supported by the side boards adjacent the opposite ends thereof, the shaft of one of the drums extending beyond the side of the container, drums fixed to the shafts, an endless conveyer disposed around the drums, means for imparting movement to the side boards, longitudinally of the trackways in either direction, and a driven member carried by a side of the container adjacent an end thereof, said driven member operatively engaging the extended portion of the shaft when the side boards are at the limit of their movement in one direction.

2. In combination with a container provided with parallel trackways at the upper portions of the sides thereof, side boards slidably engaged with said trackways, drums rotatably supported by the side boards adjacent the opposite ends thereof, an endless conveyer disposed around the drum, means for imparting movement to the side boards longitudinally of the trackways in either direction, a driving means operatively engaged with one of the drums when the side boards are at the limit of their movement in one direction, and a second conveyer carried by the container and disposed upwardly and inwardly on a predetermined incline, said second conveyer discharging upon the conveyer when said conveyer is operatively engaged with the driving means.

3. In combination with a container provided with parallel trackways at the upper portions of the sides thereof, side boards slidably engaged with said trackways, drums rotatably supported by the side boards adjacent the opposite ends thereof, an endless conveyer disposed around the drum, means for imparting movement to the

side boards longitudinally of the trackways in either direction, a driving means operatively engaged with one of the drums when the side boards are at the limit of their movement in one direction, and a second conveyer carried by the container and disposed upwardly and inwardly on a predetermined incline, said conveyer including a movable member discharging upon the conveyer when said first named conveyer is operatively engaged with the driving means, said movable member of the second conveyer being operatively engaged with the driving means first named for the conveyer irrespective of the position of the side boards.

4. In combination with a container provided with parallel trackways at the upper portions of the sides thereof, side boards slidably engaged with said trackways, corresponding end portion of the side boards being provided with upstanding extensions,

the opposite end portions of the side boards being provided with depending extensions, drums rotatably supported by the side boards adjacent the opposite ends thereof, an endless conveyer disposed around the drum, a winding means carried by one end portion of the container, a flexible connection between said winding means and the extension at the adjacent end of each of the side boards, a second winding means carried by the opposite end portion of the container and a flexible connection operatively engaged with said second named winding means and the adjacent end portion of each of the side boards.

In testimony whereof I hereunto affix my signature in the presence of two witnesses.

HENRY BLOOMER.
